UNITED STATES PATENT OFFICE.

ERNEST JONES, OF BIRMINGHAM, ENGLAND.

BRACELET AND SIMILAR ARTICLE.

1,103,776.

Specification of Letters Patent. Patented July 14, 1914.

Application filed November 15, 1912. Serial No. 731,598.

To all whom it may concern:

Be it known that I, ERNEST JONES, subject of the King of Great Britain, residing at 114 Vyse street, Birmingham, England, 5 have invented certain new and useful Improvements in Bracelets and Similar Articles, of which the following is a specification.

This invention has relation principally to 10 adjustable bracelets, watch and other wristlets and similar articles, but may also be applied to other adjustable articles which can be constructed of flexible chain or link work, such as adjustable chains for closing 15 the mouths of bags, purses and like receptacles.

The object of the said invention is to provide a springless bracelet or similar chain or link-work which can be readily adjusted or 20 expanded and contracted, together with positively-operating means for adjusting such chain and for securing the same after adjustment.

According to the invention I propose to 25 make up the bracelet or other article from a series of chain-links which are so constructed and connected as to be slidable relative to one another, and in conjunction with this chain, to use a small adjusting chain or 30 cord which is passed through either the whole or some of the said links, and is connected to a mechanical device for winding up or shortening the adjusting chain and thereby closing or contracting the bracelet 35 chain. The winding device is also adapted to serve as a fastening which positively secures the bracelet in its contracted condition.

Figure 1 of the accompanying drawings 40 is an elevation (partly in section) of an adjustable watch-wristlet constructed in accordance with one form of my invention and provided with a self-retaining adjusting and fastening device. Fig. 2 represents upon an 45 enlarged scale, a side elevation of a part of the main link-work. Fig. 3 is a horizontal sectional plan of Fig. 2 showing how adjusting-chain guides are embodied in each alternate link of the main chain, also the arrangements which provide for the relative sliding 50 movement of the main links. Figs. 4, 5 and 6 respectively represent cross sectional views of Fig. 3, taken upon the dotted lines α , α^1 and α^2 . Fig. 7 is a horizontal section, on a 55 further enlarged scale, showing the construction of the self-retaining winding and

locking device for taking up and paying out the adjusting chains. Fig. 8 is a horizontal section of the self-retaining winder taken upon the dotted line α^3 Fig. 7. Fig. 9 is another sectional view taken upon the dotted line α^4 Fig. 7. Fig. 10 is a cross sectional view of an alternative construction of winding drum wherein the winding device is locked by a positively-operated arrangement 60 which provides for the adjustment of the bracelet by rotating the winding drum in either direction. This view shows the parts in the positions they assume when the rotatable parts of the winder are locked. Fig. 70 11 is a similar view to Fig. 10 but shows the positions the parts assume when the rotatable drum is released to admit of its movement for taking up or paying out the adjusting chains. Figs. 12 and 13 are two 75 horizontal sectional views taken upon the dotted line α^5 Fig. 10 showing the winder-fastening devices in their engaged and disengaged positions respectively. Fig. 14 represents, in two different sections and in 80 plan, the stationary parts of the winding device in which the drum-locking bolts are mounted. Fig. 15 shows in section, a modified winding and locking device embodying a spring which is tensioned when the bracelet 85 is expanded and takes up the adjusting chains automatically when released.

The same letters of reference indicate corresponding parts in the several figures of the drawings.

Describing first the general arrangement of the link-work of the adjustable wristlet and the winding and locking mechanism represented in Figs. 1 to 9, the said wristlet comprises two adjustable lengths of chain 90 A, A^1 , each consisting of an assemblage of relatively slidable links a , b , and I provide each alternate link a with a small tubular guide g , wherethrough the adjusting chains are passed. These chains A, A^1 are respectively anchored, at one end a^1 to suitable attachments a^2 on the opposite sides of the watch case c^1 , while the links a^3 at their other extremities are anchored to the opposite sides of a small case d^1 containing the 100 winding mechanism, which consists of a rotary drum d connected to an external disk d^2 having knurled edges or carrying a small hinged handle d^3 or other means whereby the drum may be rotated by the thumb and 105 finger. In conjunction with the said drum I arrange a ratchet and pawl e , e^1 , for posi-

tively holding the same after it has been rotated: the ratchet e being affixed to the winding drum, while the spring-actuated pawl e^1 is pivoted to the bottom of the case 5 and is extended through a slot in the side of said case to form a release-pusher e^2 .

Through the guides in the alternate links a of each section of the bracelet chain, I pass a length of small chain f (or flexible cord) one end f^1 being fastened to an anchoring device carried by the adjacent attachment a^2 on the watch case, while the other extremity is passed through an aperture d^4 in the side of the winder box and is 15 attached to the inclosed drum as shown in Fig. 9. With such an arrangement, when the adjusting cords or chains are unwound, the bracelet is expanded to its maximum size and can readily be passed over the hand on 20 to the wrist. Then by rotating the winding device, the ends of the said chains are taken up around the drum and simultaneously the relatively-slid bracelet links confined between the watch case and the winder box are 25 gathered or drawn together around the wrist until the bracelet fits firmly in its place thereon.

The self-engaging device e , e^1 , by holding the drum after the adjustment has been made, 30 positively locks the bracelet on the wrist and obviates any possibility of the same becoming detached, while when it is desired to remove the bracelet, it is merely necessary to press the pusher e^2 so as to disengage the pawl and free the winding drum to allow the adjusting chains to be drawn out to their full length with the bracelet chain.

In the bracelet-chain construction shown, the relative sliding movement of the links 40 is provided for by arranging the pins a^5 (which connect the chain-guides g to the side plates a^6 of the alternate links a) to work in longitudinal slots b^5 in the side plates of the links b as clearly shown in 45 Figs. 4, 5 and 6. I may, however, adopt any other constructions which will admit of the desired movement when the adjusting chain is taken up or paid out, and may also modify the form and arrangement of the chain-guides as desired.

The terminal links of the bracelet-chain and the ends of the adjusting chain may also be anchored by any other suitable means than those embodied in the watch-wristlet 55 represented in the drawings, while in the case of ordinary expanding bracelets and like adjustable chains, instead of two lengths of adjusting chain or cord, I may use a single length which passes right through the 60 bracelet chain, and is connected at its opposite ends to the winding drum: or one end only of the said chain may be attached to the said drum while the other end is anchored to the winding drum casing. The opposite extremities of the single bracelet chain are, in

this construction, anchored respectively to the opposite sides of the winding-drum casing.

The winding arrangements described in connection with the bracelet shown in Figs. 1 to 9 only admit of the adjusting chain being taken up when the winding drum is rotated in one particular direction, but the construction represented in Figs. 10 to 14 provides an effective means of adjustment 70 which is operative for taking up the adjusting chain, when rotated in either direction, so that there is no liability of the same being damaged by the user endeavoring to turn the winding drum the wrong way. The 75 locking and releasing mechanism is positive in both its actions. In the arrangement shown in the said Figs. 10 to 14, the casing d^1 of the winding device is connected with the bracelet link-work as described in connection with Figs. 1 to 9, and the extremities of the adjusting chain f are passed through apertures d^4 in the said box and attached to winding drum d , which (after the bracelet 80 has been fully expanded) may be rotated in 85 either direction to take up the ends of the adjusting chain. This drum, which is rigidly connected to a rotatable operating disk d^3 that also constitutes the cover of the box d^1 , surrounds a sleeve d^6 which occupies the 90 center of, and is rigidly attached to the body of the said box, and as this body is anchored directly to the end-links of the bracelet, both it and the central sleeve are 95 stationary relative to the rotatable drum-operating disk. This sleeve is also utilized as a carrier for an externally-controlled arrangement of bolts or fasteners whereby the operating disk and drum are positively locked to the box body after the adjustment of the 100 chain, and for this purpose, the upper end of said sleeve is extended to within a short distance of the rotatable disk and has attached to it, a guide d^7 of suitable section 105 which is furnished with a pair of slideable 110 bolts g^1 , g^2 . The outer ends of these bolts are adapted to engage with an annular series 115 of teeth h , carried by the drum-operating disk d^3 , while their inner ends are arranged so that they have contact at g^2 with cam-acting edges i^1 on a pusher i , which is carried by the sleeve d^6 and extends outwardly 120 through an opening in the center of the relatively-rotatable disk; the outer end of the 125 said pusher being preferably provided with a small head, so that the same can be forced inwardly by finger pressure, or withdrawn by the thumb and finger. The said bolt-operating pusher (which works at a right angle to the bolts) carries at its lower end, a 130 small sleeve i^3 containing a spiral spring i^4 whose ends make frictional contact with the inside of the central sleeve d^6 for retaining the said pusher in any position in which it may be placed. The sleeve i^3 also acts as a 135

stop to prevent the pusher being detached when the same is drawn out as shown in Fig. 11. These several parts are so arranged that, when the pusher is pressed inward into the box (see Fig. 10) after the adjusting chain has been wound up to the desired extent, its cams i^1 act upon the bolts at g^2 and force the latter apart so that their outer ends are engaged with the teeth on the drum-operating disk which is thereby locked to the bolt-carrier and consequently to the body of the device, (see Figs. 10 and 12) so that the adjusting chain and the contracted links of the bracket are positively secured. On the other hand, when the pusher is withdrawn (see Figs. 11 and 13) the winding drum is free to be rotated for paying out the chain and permitting the expansion of the bracelet. If the pusher is withdrawn when the bracelet is in position on a wrist, the slight pull which is necessary to actuate the said pusher is also sufficient to pull the adjusting chain off the released winding drum, and thus the locking device is unfastened and the bracelet expanded by the one movement.

Instead of using a pair of sliding bolts operated or controlled by a sliding pusher, I may employ only a single bolt: or instead of controlling the bolt or bolts by a device having an inward and outward sliding action, I may employ a small rotary cam piece which is mounted on a central sleeve or other support in rigid connection with the body of the drum-containing box, and is connected to an external device suitable for actuating the said cam without interfering with the independent rotation of the drum-operating disk.

A spring or springs may be used to withdraw or disengage the bolts when released by the controlling cam; or the cam or push piece may be arranged so that same will both engage and disengage the said bolts, but if the teeth on the operating disk are suitably curved or rounded (as shown in Figs. 12 and 13) their action on the engaging ends of the bolts under the pull of the wound-up chain will suffice to take the said bolt ends clear as soon as the restraint of the controlling slide or cam is removed. Further, I do not confine myself to the arrangements above described, but may use any externally-controlled positively-acting bolt or locking mechanism which, when the bolts are withdrawn, will admit of the drum-operating disk being rotated (preferably in either direction) for winding up or paying out the adjusting chain.

In the arrangement represented in Fig. 15, the winding drum d to which the extremities of the adjusting chains f are connected, contains a volute spring m , one end of which is attached to the said drum while the other end is secured to a stationary part,

such as the central sleeve d^5 carried by the winding box or casing d^1 : the arrangement being such that the said spring m is wound up or tensioned when the adjusting chains are drawn out by the expansion of the bracelet, while when the expanding pull on the said chains is relieved, the spring operates automatically to draw in the chains and either adjust the bracelet to the wrist or contract the same to its minimum size, as the case may be. In order to secure the bracelet in its adjusted position when the spring is tensioned, I may use a ratchet on the said drum in combination with a push-released pawl such as shown in Figs. 1 to 9, or any other suitable arrangement, but in the device shown in Fig. 15, the locking means operates to prevent movement of the winding drum in either direction, and consists of a slide n , mounted in the central sleeve d^5 and provided with lateral projections n^1 adapted (when the said slide is depressed) to engage simultaneously with notches d^{16} d^7 , in the upper edges of the winder drum d and sleeve d^5 so as to rigidly secure these two latter parts to one another, while when the said projections are disengaged by the lifting of the slide, the spring is free to rotate the drum in the proper direction for automatically taking up the adjusting chains.

The particular application of the various forms of the invention to the other flexible and adjustable chain-work articles before mentioned differs in no essential respect from their application to watch wristlets and bracelets as herein described.

Having described my invention, what I claim and desire to secure by Letters Patent is:—

1. In a flexible and adjustable bracelet or the like, the combination of a chain composed of links which are slidable relatively to one another circumferentially of the bracelet, a member to which the end links of said chain are anchored, and an inelastic, flexible element passed through said links, whereby movement of the ends of said element toward each other will effect the sliding movement of said links.

2. In a flexible and adjustable bracelet or the like, the combination of a chain composed of links which are slidable relatively to one another circumferentially of the bracelet, certain of which links are provided with central guides, a member to which the end links of said chain are anchored, and an inelastic, flexible element passed through said links and guides, whereby movement of the ends of said element toward each other will effect the sliding movement of said links.

3. In a flexible and adjustable bracelet or the like, the combination of a chain, the adjacent, component links of which have pin-

and-slot connections, to permit relative sliding movement thereof circumferentially of the bracelet, a member to which the end links of said chain are anchored, and an inelastic, flexible element passed through said links, whereby movement of the ends of said element toward each other will effect the sliding movement of said links.

In testimony whereof I have hereunto set my hand in presence of two subscribing witnesses. 10

ERNEST JONES.
